UNITED STATES PATENT OFFICE

GEORGE M. McCANN, OF NEW CASTLE, DELAWARE

BREECH-BLOCK-OPERATING MECHANISM

Application filed October 28, 1930. Serial No. 491,722.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

The invention relates to a breech block operating mechanism and is an improvement on the type of mechanism shown in Patent No. 996,569 of June 27, 1911.

10 In the patent a yielding cam arrangement is provided whereby the gun is allowed to recoil freely with the breech closed, but on counterrecoil the cam is effective to rotate a crank which opens the block. During 15 the final opening of the block the extractors are functioned as in Patent No. 1,393, 353 of October 11, 1921, to withdraw the cartridge case and lock the block in the open position. Frequent failure of the extractors to hold the block open has led to 20 the present improvement which relates to the block opening mechanism but affects the functioning of the extractor in holding the block open.

25 According to the invention the block opening mechanism is modified to provide a more gradual and an additional movement of the block whereby a time interval is obtained in which the extractors may be assuredly positioned before being engaged by the block.

30 With the foregoing and other objects in view, the invention resides in the novel arrangement and combination of parts and in the details of construction hereinafter described and claimed, it being understood that changes in the precise embodiment of the invention herein disclosed may be made 35 within the scope of what is claimed without departing from the spirit of the invention.

40 A practical embodiment of the invention is illustrated in the accompanying drawings, wherein:

Fig. 1 is a view in front elevation of the improved operating mechanism;

Fig. 2 is a sectional view on the line 2—2 of Fig. 1;

Fig. 3 is a view in side elevation and 50 partly in section of a breech block in closed position and showing the extractors;

Fig. 4 is a fragmentary view showing the manner in which the extractors and block cooperate to hold the block in the open 55 position;

Fig. 5 is a similar view showing the position of the block when the crank leaves the cam guide.

Referring to the drawings by characters 60 of reference:

In Fig. 3 there is shown a gun 4 of the reciprocating type provided with a vertically sliding breech block 5 which is opened and closed by an operating shaft 6 and crank 7 in a well known manner. The shaft carries a handle 8 for manual control and is attached to a spring mechanism 9 for closing the block. The cartridge extractors 10 are of the type shown in the patents hereinbefore referred to and have the inside trunnion 11 flattened as at 12 for engagement with a shoulder 13 of the block whereby the block is locked in the open position (Fig. 4), the faces 14 and 15 of the extractor being in contact respectively with the gun 4 and the block 6. A spring-pressed plunger 16 normally tends to hold the extractor in the locking position. The trunnion 11 is disposed in a cam groove 17 in 70 the block and a corresponding trunnion cut away in Figs. 3 and 4 is supported by the breech ring of the gun. 75

Referring to Figs. 1 and 3 the left hand end of the operating shaft 6 carries a crank 85 18, which, in the in battery position of the gun is positioned forwardly of its actuating mechanism.

This mechanism consists essentially of a cam plate 19 having a large trunnion 20 90

mounted in the manner shown in Patent No. 996,569 in a plate 21 secured to the cradle plate 22. The rotatable cam plate is provided with shoulders 23 and 24 engageable 5 respectively with correspondingly shaped faces 25 and 26 in the plate 21 whereby rotational movement of the cam plate is limited. The shoulder 23 limits movement of the cam plate due to the action of the spring 10 27 and the shoulder 24 limits movement due to depression of the cam plate when the head 28 of the crank 18 rides over the upper face 29 of the cam during recoil of the gun. When the shoulder 23 is in engagement with 15 the face 25 the cam plate 19 is rigidly held so that the head 28 of the crank in riding along the lower face 30 will cause the crank 18 and shaft 6 to be rotated to open the breech block.

20 A second cam plate 31 is rigidly secured to the plate 21 by means of screws 32 which in turn are locked by set screws 33. This fixed cam is in prolongation of the rotatable cam 19 and its rearmost end 34 preferably 25 extends across the axis of rotation of the cam 19. The cam face 35 of the cam 31 is of less inclination than the lower face 30 of the rotatable cam and its origin *a* is spaced a slight distance from the termination 30 *b* of the face 30.

In the normal position of the parts prior to firing the gun, the breech block is closed as in Fig. 3 and the relation between the fixed and rotatable cam is as shown in Fig. 35 1. The gun on being fired moves rearwardly in recoil and the head 28 of the crank 18 rides over and rocks the rotatable cam. On counterrecoil of the gun the head 28 engages the lower face 30 of the 40 cam and as a result the crank and the shaft 6 are rotated to open or lower the breech block against the action of the spring mechanism 9.

When the head 28 of the crank 18 is at the 45 point *b* of the cam face 30 the breech block is in the position shown in Fig. 4, the trunnion 11 of the extractor having left the cam groove 17 and in doing so caused retraction of the extractors. Up to this point 50 the action closely follows that of the operating mechanism shown in the patents. It will be noted that on retraction of the extractors, the face 15 of the extractors strikes the breech block and has a tendency 55 to rebound and vibrate, thereby angularly moving the flattened face 12 of the trunnion 11 and also bodily displacing the trunnion to the rear. This vibratory action is supposed to be neutralized by the spring- 60 pressed plunger 16 (Fig. 1) which urges the lower portion of the extractors forwardly but the action is not positive. As a consequence, if the lowering or holding of the block is discontinued as by the crank 18 65 clearing the cam 19, the spring mechanism

9 is immediately effective to raise the block, and if the trunnion 11 is not fully forward to present its flattened face 12 parallel to the shoulder 13 of the block, the block instead of being restrained by the extractor will exert a camming action on the trunnion 11 and force it rearwardly into the cam groove 17. With the extractors thus removed the breech block moves to the closed position.

In the arrangement provided in the present invention, the crank is rotated very gradually and is restrained and stabilized by the fixed cam 31 after leaving the rotatable cam 19. During the travel of the 75 crank between the points *b* and *a* on the two cams there is a slight counter-rotation of the crank permitting a correspondingly slight and momentary raising of the block for the purpose of allowing the shoulder 13 of the block to engage the flattened end 12 of the extractor trunnion and serve to steady the extractor and reduce vibration to a minimum. The crank then rides down the face 35 of the fixed cam 31 to cause a further lowering of the breech block to the position shown in Fig. 5 and provide a time interval which will insure the correct positioning of the extractor in a state of rest before the shoulder 13 of the rising breech 95 block engages the flattened face 12 of the extractor trunnion 11. The breech block is free to be raised by the spring mechanism 9 when the crank clears the non-inclined face 36 of the fixed cam 31.

I claim:

1. In a gun, the combination with a breech block, a crank shaft for operating the block and extractors for holding the block open, of a cam arrangement including a rotatably mounted cam yielding to the crank on recoil and effective to rock the crank on counter recoil to position the block for engagement of the extractors, a fixed cam in prolongation of the rotatable cam but spaced therefrom, said fixed cam effective to rock the crank shaft to lower the block below the position of its engagement with the extractors.

2. In a gun, the combination with a breech block, a crank shaft for operating the block and extractors for holding the block open, of a cam arrangement including a rotatably mounted cam yielding to the crank on recoil and effective to rock the crank on counter recoil to position the block for engagement of the extractors, a fixed cam in prolongation of the rotatable cam and effective to rock the crank shaft to lower the block below the position of its engagement with the extractors.

3. In a gun, a breech block, a crank shaft for operating the block, a cam arrangement including a rotatably mounted cam yielding to the crank on recoil and effective to rock

the crank on counter recoil, and a fixed cam in prolongation of the rotatable cam and effective to additionally rock the crank shaft.

- 5 4. In a gun, a breech block, a crank shaft for operating the block, a cam arrangement including a rotatably mounted cam yielding to the crank on recoil and effective to rock the crank on counter recoil, and a fixed 10 member for stabilizing the crank after it leaves the rotatable cam.
